UNITED STATES PATENT OFFICE.

CHARLES JOHNSTON AND CLAUDE JOHNSTON, OF MEMPHIS, TENNESSEE.

INDIVIDUAL OR GROUP CUT-OUTS FOR ELECTRICAL DEVICES.

1,138,222.

Specification of Letters Patent.

Patented May 4, 1915.

Application filed March 21, 1911, Serial No. 616,042. Renewed September 29, 1913. Serial No. 792,486.

To all whom it may concern:

Be it known that we, CHARLES JOHNSTON and CLAUDE JOHNSTON, both citizens of the United States, residing at Memphis, in the county of Shelby and State of Tennessee, have invented certain new and useful Improvements in Individual or Group Cut-Outs for Electrical Devices, of which the following is a specification.

10 Our invention relates to individual or group cut outs for electrical devices.

The object of the invention is to provide means to readily and effectively control the independent operation of electric devices, such as lamps, signs, motors, etc., connected in parallel from a distant control station and at the same time to avoid burning out the contact points at the local circuit when the circuit is made and broken in cutting in or out the object controlled.

20 To this end our invention comprises, generally stated, means at the central control station, for momentarily effecting the lowering of the voltage in the circuit, and thereby electrically releasing a member which is actuated by gravity and serves in its successive movements to actuate a make and break device to alternately close and open a shunt circuit governing the particular device or 30 devices to be controlled.

Our invention is illustrated in the accompanying drawings in which—

Figure 1 is a view showing the individual local controlling device in front elevation and showing the main circuit diagrammatically, and Fig. 2 is a detail view of the rear face of the make and break device.

Referring to the drawings, 1 and 2 are the main feed lines leading from and to the central power station and 3 designates a resistance which may be thrown into circuit with the feed lines or shunted by a switch 3'. However, any suitable means arranged at any suitable location may be employed to 45 effect the same function as the resistance and switch. A number of lamps 4, 5, 6 are connected in parallel or multiple and supplied with current from the main feeds. Instead 50 of the lamps, motors, signs or other translating devices may be utilized in connection with our invention. The lamp 5 is the one to which the independent cut out mechanism is shown as applied. This lamp is connected in series with separated, fixed contact plates

7, 8 mounted on the base-board 9, and to 55 which are respectively connected the leading in wires 10, 11.

Mounted on the base-board 9 is a solenoid 12 having its magnet connected in parallel upon the main feed lines forming a shunt 60 across them through leading in wire 10 and leading in wire 12. This solenoid has a vertically movable gravity-actuated core 14. In the drawings the core is shown dropped to its lower position, the solenoid being de-energized. Projecting from the lower end of the core is an arm 15 on which is pivoted a pawl 16 extending at substantially a right angle to the core and held yieldingly in a normal horizontal position by means of the saddle spring 17 secured to the end of the core. This pawl is adapted to engage the ratchet teeth 18 of a rotatable ratchet wheel 19 mounted on a plate 20 fixed to the base-board 9. This wheel is adapted to be moved 65 from right to left by the actuating pawl and its teeth are inclined at the ends to permit the passage of the yielding pawl past the teeth in the upward movement of the pawl when the core is raised. A bent spring 21 70 fastened upon the axle screw of the wheel serves to exert pressure at its ends against the hub of the wheel to prevent backward movement of the latter and to hold it in the position to which it is moved by the actuation of the pawl. The wheel is preferably 75 provided with eight teeth so as to be moved by the pawl one-eighth of a revolution upon each actuation. Upon the inner surface of the wheel are mounted four separated lugs 80 22 arranged in a circle. These lugs are adapted to alternately engage and release a switch lever 23 pivoted on the plate 20 at 24. The lever is provided with a shoulder 25, a notch 26 and a forward inclined hook-shaped end 27. At its rear end, the lever carries a sliding contact plate 28 adapted to bridge the contacts 7 and 8 when moved upward by the lever, serving to alternately make and break the circuit between these contacts so as to cut in or cut out the lamp or other translating device to be controlled. The sliding movement of the bridging contact plate is effected by the engagement of one of the lugs on the ratchet wheel with the shoulder 25 on the lever which moves the plate into engagement with the upper contact plate 8, the lug then passing into the

notch 26 and holding the bridge plate in closing position and the breaking of such contact is effected by the next movement of the same lug in the same direction against the forward sloping end 27 of the lever which tilts the lever in the opposite direction on its pivot and carries the bridging contact plate away from the upper contact, thus breaking the circuit and cutting out the lamp.

The operation is as follows:—Upon the momentary lowering of the voltage in the main circuit at the central control station, the solenoid will be deenergized and the core 14 will be released and will drop by gravity, its pawl 16 striking against one of the teeth on the ratchet wheel and turning the latter one tooth and carrying one of the lugs 22 either into closing or without drawing contact with the lever 23. This lever will thus be shifted to either carry the bridging contact into engagement with the two contacts 7 and 8 or to remove it therefrom, thus either making or breaking the circuit through the lamp. The successive movements of the ratchet wheel will alternately make and break the circuit. The restoration of the full voltage in the main circuit after the momentary lowering of said voltage, will immediately reenergize the solenoid lifting the core within the same, and in such upward movement, the yielding pawl of the core will freely pass the sloping teeth of the ratchet wheel without turning the latter.

It will be seen that the actuating member consisting of the core and its pawl is electrically released and is caused to move by gravity, thus avoiding the necessity of having the solenoid in an energized condition when the circuit is broken at the contact points, thereby preventing burning of these points, such as would be the case if the current were permitted to remain on while the circuit is broken at this point.

It will be noted that throughout the entire operation of this device, the actuating wheel and movable arm, which carries the sliding contact plate, are not moved in any way until the movable core drops at the lowering of voltage on the main lines, at which time owing to the extremely low voltage passing through the contacts when the lamp is in circuit, there can be no possibility of burning at the make and break of contacts. For example, if a live circuit of say one hundred volts operating a lamp taking six amperes is broken, there will be much burning at the metallic points when the break is made; but if an electric circuit remains closed through a lamp taking six amperes at one hundred volts until the said voltage is lowered to say one volt, then there can be no arcing or burning at make and break contacts.

Having thus described our invention, what we claim is:—

1. In combination with a main electric circuit containing a plurality of translating devices, a local circuit controlling one or more of said devices and having a make and break device therein, and means operable to either make or break the local circuit upon the lessening of the current strength in the main circuit, substantially as described. 75

2. An electric circuit having a plurality of translating devices, a solenoid in said circuit having a downwardly movable core operable only upon the deenergization of the solenoid, means actuated by said core for 80 closing or opening the circuit through one or more of said devices, and distant control means for momentarily lowering the voltage of said circuit.

3. An electric circuit having a plurality 85 of translating devices, a local cut-out for one or more of said translating devices, means to operate said cut out to either make or break the circuit through said translating devices upon the momentary lowering of the 90 voltage in the main circuit without breaking said main circuit and central station means to effect such momentary lowering of the voltage.

4. In an electrically connected system of 95 translating devices, a metallic local circuit means operated by gravity to alternately open and close said metallic local circuit to cut in or out one or more of said devices and means to release said gravity operated 100 means by a momentary lowering of a given voltage in the main circuit without breaking said circuit.

5. An electric circuit containing a plurality 105 of translating devices connected in parallel, a local make and break contact device controlling the circuit through one or more of said translating devices, having the contacts connected in series with said controlled devices, and an electrically released gravity actuated solenoid core for actuating in its downward movement said make and break device to either open or close the same and distant control means operating through 110 said circuit to release said core. 115

6. An electric circuit containing a plurality 120 of translating devices in parallel, a switch for cutting in or out one or more of the devices independently of the rest, a solenoid in parallel with the translating devices, a gravity drop core for both opening and closing said switch by its downward movement, and means at a distant control station for controlling the current through said solenoid to close and open said switch. 125

7. An electric circuit containing a plurality 130 of translating devices, in combination with a switch for cutting in or out one or more of said devices, separated contact points, a switch contact lever, a rotatable

wheel having projections for alternately shifting said lever into opening and closing positions, a movable weight for turning said wheel and means at a distant control station for releasing said weight by the momentary lowering of the voltage only through the circuit.

In testimony whereof we have affixed our signatures in presence of two witnesses.
